UNITED STATES PATENT OFFICE.

THEODOR HARBERS, OF LEIPZIG, GERMANY.

PHOTOGRAPHIC-PRINTING APPARATUS.

1,156,528.

Specification of Letters Patent.

Patented Oct. 12, 1915.

Application filed June 26, 1913, Serial No. 775,922. Renewed July 22, 1915. Serial No. 41,396.

To all whom it may concern:

Be it known that I, THEODOR HARBERS, a subject of the King of Saxony, residing at Machern 81^F, Bezirk Leipzig, Germany, 5 merchant, (whose post-office address is Machern 81^F, Bezirk Leipzig, Germany,) have invented certain new and useful Improvements in Photographic-Printing Apparatus, of which the following is a specification.

The present invention has for its object an apparatus for copying photographic negatives.

Although the invention will greatly appeal to amateur photographers, it will also be found useful by professional photographers, because owing to the small size and the simplicity of the apparatus it can readily be carried about.

20 The invention is applicable to quick copying papers, silver bromid, and gas-light papers, which permit of making the prints by artificial light.

The apparatus is illustrated in the accompanying drawing, in which: Figure 1 is a perspective top view, Fig. 2 is a longitudinal section, and Fig. 3 shows the lamp to a larger scale.

25 The apparatus consists of a box *a* containing a compartment *b* in which an electric battery *c* is arranged. Upon the bottom of the main compartment of the box *a* an electric incandescent lamp *d* is arranged; this lamp is electrically connected with the 30 battery *c*, the connection being interrupted owing to the fact that one of the poles terminates in a metal plate *e* fixed to the edge of the box while the other terminal is formed by the spring pole piece *f* of the battery.

35 40 When the two poles *e* and *f* are connected the circuit is closed and the lamp *d* lighted. This bridging of the poles *e* and *f* is effected by a metallic spring *g* secured to the lid of the box *a*. The lid, which is hinged to one side 45 of the box *a*, consists of two parts *h* and *i* which are hinged together. In the box *a* light-reflecting walls *k* are provided which may consist of white cardboard or the like and may be composed of inclined or curved 50 surfaces. Upon the upper edge of the box *a* a ground glass plate *m* is provided for the reception of the negative *l*. When the lid *h*—*i* is entirely removed the sensitized paper is placed upon the negative and first of 55 all retained by means of the rear portion *h* of the lid in such a manner that it can be

adjusted. The other part *i* of the lid is then closed thereby closing the contacts *e*, *f* by means of the bridge *g*. In one of the side walls of the box *a* an inspection aperture *r* 60 glazed with red glass is provided; through this opening it can be seen whether the lamp *d* is alight.

In order to permit of closing the box without at the same time closing the electric circuit, the bridging or connecting spring *g* can be turned aside as indicated in broken lines in Fig. 1.

Notwithstanding the employment of a ground glass lamp bulb and the dispersion 70 of the light by the reflecting walls, and also the ground glass plate, the illumination of the negative and of the sensitized paper is not perfectly uniform, as the middle portion receives direct light, so that over-exposure might easily occur there. Accordingly provision is made that only indirect light can fall upon the surface to be illuminated, that is to say reflected light. The top of the lamp bulb *d* is provided with a screen 80 or covering *n* which prevents direct radiation in the upward direction. Consequently the rays of light can only reach the reflecting walls *k* which throw them on to the plate, whereby a perfectly uniform illumination 85 of the negative is obtained. The top of the incandescent bulb may be covered with a coat of black paint or the like or by an appropriately shaped piece of paper or metal. If desired the screen or coat may present reflecting properties on its side directed toward the lamp.

The apparatus that has been described is characterized by its simplicity, cheapness and practical utility, particularly as the battery *c* can be replaced without difficulty.

Having fully described my invention, what I claim and desire to secure by Letters Patent is:

1. A photographic printing apparatus 100 comprising a box, a lid hinged thereto, a negative support adjacent the top of said box, an electric battery secured in said box, a circuit, a lamp secured to said box in said circuit, a pivoted contact bridge device arranged in said lid adapted to close said circuit when the lid is fastened to place, reflecting plates arranged in the box to reflect the rays onto the negative, and a screen or cover on the top of the lamp bulb to prevent direct rays from reaching the negative, 105 substantially as described.

2. A photographic printing apparatus comprising a box, a lid therefor, an electric battery contained in said box, a circuit, a lamp secured in said box connected in said circuit, a negative, a support therefor adjacent the lid of said box, a pivoted contact bridge device arranged upon the lid of the box, for completing the circuit when the lid is closed, reflecting plates arranged in the box to reflect the rays on the negative, and

an opaque cover provided for said lamp serving to prevent direct rays from reaching the negative.

In testimony whereof I have hereunto set my hand in presence of two subscribing witnesses this 13th day of June 1913.

THEODOR HARBERS.
